DISPENSING ARRANGEMENT

James L. Hippel, Frederick L. Dewey, and Burton F. Burnett, Canton, Ill., assignors to International Harvester Company, a corporation of New Jersey

Application June 19, 1942, Serial No. 447,694

3 Claims. (Cl. 111—59)

This invention relates to dispensing arrangements adapted for attachment to tractors or tool-supporting structures and, more particularly, to a means for drivingly connecting together self-contained, ground-driven material-dispensing units.

It is an object of the present invention to provide self-contained dispensing units adapted for attachment to transversely extending tool-attaching portions or tool bars for lateral adjustment thereon and means for the coupling together of the dispensing units whereby the ground drive wheel of one unit may drive the other dispensing unit.

It is another object of the invention to provide a material-dispensing arrangement which can be readily assembled and disassembled from a tool-supporting structure and at the same time easily adjustable laterally on the tool-supporting structure.

According to the present invention, self-contained, ground-driven, material-dispensing units are adapted for independent attachment to a transversely extending tool-attaching portion or tool bar and in such a manner that the same may be laterally adjustable thereon. Each of said material-dispensing units includes a ground drive wheel adapted for driving the same and, in order to maintain simultaneous dispensing of material, the ground drive wheel of one unit is attached to the ground drive wheel of the other unit. Should one of the ground drive wheels of a unit be momentarily cleared of the ground, the unit will still be driven by the ground drive wheel of the other unit. There is a separable connection between the ground drive wheels whereby the units may be readily separated from or attached to one another as they are detached from the tool bar. This separable connection means includes the provision of telescoping parts respectively carried by the units. The ground drive wheel also serves as a means for gauging the working position of the dispensing unit and of the tool bar. On the bracket structure, which connects the ground drive wheel to the tool bar, is mounted a manually adjustable means for vertically adjusting the ground drive wheel. This adjustable means is thus carried by the bracket structure and forms a part of the unit and hence is adjustable laterally along the tool bar with the unit. Its lever is accessible to the operator at the operator's station on the tool-supporting structure.

For other objects and for a better understanding of the invention, reference may be had to

the following detailed description taken in conjunction with the accompanying drawings, in which:

Figure 1 is a view in elevation of a tractor with one wheel removed and with the dispensing unit embodying the features of the present invention connected thereto;

Figure 2 is a plan view of the rear portion of the tractor and of the dispensing arrangement;

Figure 3 is a large detail view of a single material-dispensing unit and illustrating its attachment to a transverse tool bar; and

Figure 4 is a detail arrangement of the separable connection means arranged for connecting together the ground wheels of the laterally spaced dispensing units.

Referring now to the drawings and more particularly to Figures 1 and 2, there is shown a tractor 10 having a rear portion 11 with a transversely extending rear axle structure 12 supported on rear traction wheels 13. Located on the rear portion 11 is an operator's station 14 accessible to a steering wheel 15.

Connected to the rear axle structure 12 by quick-attachable means 16, well known in the art, is a supporting frame structure 17 having a vertically movable, transversely extending tool bar 18 carried by vertically extending members 19 which are in turn connected to the frame structure 17 by means of upper and lower links 20 and 21. Both ends of these links are respectively pivotally connected to the vertically extending members 19 and the frame structure 17 to allow for free vertical movement of the tool bar with respect to the tractor. It should now be apparent that the tractor and the tool-supporting frame with its vertically movable tool bar 18 provide in their entirety a tool-supporting structure to which self-contained, ground-driven, material-dispensing units 22 may be readily attached.

The tool bar or attaching portion 18 with the material-dispensing units on the same can be vertically moved to a transport position on the tractor. This is effected by the usual fluid lifting arrangement including power-operated devices 23 located respectively at opposite sides of the tractor and arranged to react against the rear axle structure 12 by being anchored to the quick-attachable means thereon, as indicated at 24. The forward end of these power-operated devices is supported on fore and aft swingable links 25 pivoted at 26 on a fluid supply housing 27 carried within the body of the tractor 10 forwardly of the rear axle structure 12. Fluid is

delivered from the fluid supply source to the power-operated devices 23 by means of fluid communications 28. When it is desired to extend the fluid-operated devices 23, the operator, seated on the operator's station 14, thrusts forwardly a control rod 29, which is connected to an arm 30 extending from the fluid supply housing 27 within the tractor.

As these power-operated devices are extended, connecting links 31 are carried forwardly to rotate a rockable structure 32 pivoted on the supporting frame 17 and connected respectively by means of lifting links 33 and 34 to the lower links 21 of the tool-supporting structure. The lifting link 33 includes an adjustable mechanism 35 accessible to the operator's station 14 for leveling the tool bar 18, there being looseness in the connection of the links with the vertical frame structure 17 and the vertically extending members 19. The rockable structure 32 includes a transversely extending rock-shaft 36, through which horizontal stabilization of the tool bar is effected, the power-operating devices 23 being of the single acting type and their pistons being freely slideable when the fluid in their cylinder has been returned to the fluid-supply source. Freedom of movement of the tool bar is possible at all times except when the power-operated devices 23 have been extended to effect lifting of the tool bar 18 and its attached units to a transverse position on the tractor, as when the operator pushes forwardly on the control rod 29.

Referring now particularly to Figure 3, there is shown the material-dispensing unit which is adapted for attachment to the transverse tool bar 18. This unit includes a vertically extending supporting bracket 37 bent rearwardly at its upper end and having intermediate its ends a V-shaped notch 38 adapted to fit over a portion of the tool bar 18. This tool bar is of square cross-section, and the notch 38 extends over two of the sides of the tool bar. The bracket 37 is rigidly retained on the tool bar by a clamping plate 39 and clamping bolts 40 adapted to be secured to the bracket 37. It will be apparent that this form of clamping arrangement with the unit may be located at any location transversely on the tool bar and that the same may be readily removed from or attached to the tool bar 18. Connected to the lower end of the bracket 37 is a furrow-opening structure 41 braced at its upper end by a bracing element 42. This furrow-opening structure trails rearwardly from the bracket structure to receive a seed spout 43 provided for the delivery of seed or other material from a seed or material container 44 supported on the upper and rearwardly turned end of the bracket structure 37. Since the dispensing of this unit is to take place on a ridge, where it is desired to provide for smoothening off of the top surfaces, there are laterally extending wing scraping elements 45 on the furrow-opening structure.

The container 44 has a drive mechanism 46 adapted to be driven in order to insure constant flow of seed and material from the container to the delivery spout 43. This means, adapted to be driven, includes a sprocket 47 which is connected by means of a chain 48 to a multiple sprocket 49 journaled on the bracket structure 37 in a journal bearing 50. From this multiple sprocket 49 is extended a chain 51 adapted to be driven from a sprocket 52 on a ground drive wheel 53. It should now be apparent that the parts 46 of the seed container 44, adapted to be driven, can be driven by the ground drive wheel 53 and that

drive connections need not be made directly with the tractor for driving these parts 46. There is an advantage in a ground-driven seed arrangement over types that are driven directly from the tractor, and that is that an adjustment of the ratio of drive of the driving mechanism need not be altered for the different tractors or for the different sizes of wheels that are disposed on the tractors. Since the units are self-contained and always have the same size driving wheel, the driving ratio of the driving mechanism remains fixed. Also, a clutch for the driving mechanism is not necessary for the ground-driven type, since the ground-driven type will automatically be shut off as the units are raised to the transport position and the drive wheel is taken out of contact with the ground.

The supporting ground drive wheel 53 is journaled on an arm 54 which is in turn pivoted on the journal bearing 50, and it is thus vertically adjustable with respect to the runner structure 41. In order to vary the planting depth of the unit, manually adjustable mechanism 55 is carried by the bracket structure and includes a lever 56 extending forwardly and accessible to the operator's station 14 on the tractor. This lever 56 is pivoted at 57 to a sub-bracket 58 secured to the upper end of the bracket 37. The lever 56 has an arm 59 which is connected by means of a link 60 to the supporting arm 54 of the supporting wheel 53. It should be apparent that as the lever 56 is adjusted, the wheel 53 will be adjusted. The lever 56 has a detent mechanism 61 adapted to engage a quadrant 62, also carried by the bracket structure 37. It should be apparent that with a unit of this type the supporting wheel 53 also serves as a gauging wheel for the tool bar 18 to which tools are connected, and that this gauging wheel 53 is carried on the same bracket structure on which the manually adjustable mechanism is carried, so that both will be adjustable laterally along the tool bar as a unit. Such a gauging arrangement has advantages over other types of connections of gauging units and adjusting mechanisms to tool bars. One is that separate brackets for the manual adjusting mechanism and the supporting or gauging element need not be provided and consequently that more adjustability can be had of such arrangement on the tool bar, since the tool bar will not be cluttered up with multiple bracket structures.

In order to perfect the driving arrangement of multiple dispensing units disposed on a transverse tool bar, there has been provided a separable connection between the ground drive wheels 53 of the respective units, whereby the ground wheel of one unit will serve to drive the ground wheel of the other unit when the ground wheel of the latter unit is out of contact with the ground, to thereby insure proper dispensing of seeds or material of both units at all times. The separable means is shown more clearly in Figures 2 and 4 and includes telescoping parts 64 and 65 slidable one within the other. These parts are connected respectively through universal joints 66 and 67 with the respective axles 68 and 69 of the ground drive wheels 53 of the respective units. Should one of the ground drive wheels 53 leave the ground, drive will be made through the telescoping parts with the drive wheel of the other unit. The telescoping part 64 is formed as a sleeve and has an opening of square cross-section adapted to receive the telescoping part 65 of solid square cross-section. Since the telescoping parts 64 and 65 overlap considerably, allowance is made for the lateral ad-

justing of the dispensing units on the tool bar 18. Also, inasmuch as the telescoping parts are easily engaged with or disengaged from each other, the units can be readily attached to or detached from the tool bar without any considerable time being necessary for loosening the driving connections between the units. Each unit is, except for the driving connections between the units, an independent and self-contained unit.

It should now be apparent that there has been provided in a planting or dispensing arrangement, a simple arrangement of self-contained planting or dispensing units, which are adaptable for independent attachment to the transverse supporting bar, and means wherein drive from one of the units may be taken from the drive of the other of the units to insure proper dispensing of seed or other material by the entire arrangement, whereby dispensing arrangements of the ground-driven type have been improved.

While various changes may be made in the construction disclosed, it will be understood that such changes shall be within the spirit and scope of the present invention as defined in the appended claims.

What is claimed is:

1. The combination with a tractor having laterally spaced rear wheels, of a tool-supporting frame connected to the tractor to be supported thereby for vertical movement to and from working position, laterally spaced material dispensing units carried by the tool-supporting frame, laterally spaced ground drive wheels between said rear wheels, means drivingly connecting said ground drive wheels to said dispensing units, and means 35 for connecting said ground drive wheels together,

whereby said dispensing units may be driven by one or the other of said ground drive wheels.

2. The combination with a tractor having laterally spaced rear wheels, of a tool-supporting frame 5 connected to the tractor to be supported thereby for vertical movement to and from working position, laterally spaced material dispensing units carried by the tool-supporting frame and laterally adjustable thereon, laterally spaced ground drive wheels carried by said frame, the spacing between said drive wheels being less than the spacing between said tractor wheels, means drivingly connecting said ground drive wheels to said dispensing units, and telescoping means for connecting 10 said ground drive wheels together, whereby said dispensing units may be driven by one or the other of said ground drive wheels.

3. The combination with a tractor having laterally spaced rear wheels of a tool-supporting frame 20 connected to the tractor to be supported thereby for vertical movement to and from working position, said frame including a transverse tool bar, laterally spaced material dispensing units carried by the tool bar and laterally adjustable thereon, a ground drive wheel for each said dispensing unit, the spacing between said drive wheels being less than the spacing between said tractor wheels, means drivingly connecting said ground drive wheels to said dispensing units, and 25 extensible means for connecting said drive wheels together, whereby said dispensing units may be driven by one or the other of said ground drive wheels.
